US00D380779S

United States Patent [19]

Shinzato

[11] Patent Number: Des. 380,779
[45] Date of Patent: **Jul. 8, 1997

[54] SIMULATION GAME MACHINE

[75] Inventor: **Yasunobu Shinzato**, Tokyo, Japan
[73] Assignee: **Sega Enterprises, Ltd.**, Tokyo, Japan
[**] Term: 14 Years
[21] Appl. No.: **47,938**
[22] Filed: **Dec. 15, 1995**
[51] LOC (6) Cl. **21-01**
[52] U.S. Cl. **D21/13**
[58] Field of Search **D21/13, 48, 1, D21/240; 463/30-37, 46, 50, 51, 52**

CLAIM

The ornamental design for a simulation game machine, as shown and described.

DESCRIPTION

FIG. 1 is a perspective view of a simulation game machine showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.
